UNITED STATES PATENT OFFICE.

JOSEPH C. TOWLER, OF SHREWSBURY, MASSACHUSETTS.

MAGNETO SUPPORT AND DRIVE.

Application filed January 13, 1923. Serial No. 612,541.

To all whom it may concern:

Be it known that I, JOSEPH C. TOWLER, a citizen of the United States, residing at Shrewsbury, in the county of Worcester and

5 State of Massachusetts, have invented a new and useful Magneto Support and Drive, of which the following is a specification.

This invention relates particularly to the provision of a suitable support and driving connections for magnetos as used to supply ignition current for automobile engines. The use of magnetos for this purpose has been much restricted on account of the labor and expense involved in attaching and providing a driving connection for a magneto on a gas engine, the cost of such attachment and connection being heretofore almost prohibitive except in cases where the engine has been originally designed for magneto ignition.

It is very often desirable to install magneto ignition in a gas engine originally designed for generator ignition and it is the object of my invention to provide a construction and arrangement of parts by which a magneto may be easily and economically provided with an attaching support and driving connections on such an engine.

It is a more specific object of my invention to provide a construction by which a magneto may be readily substituted for the distributor head commonly used for generator ignition and by which the magneto may be driven from the same point of connection to the engine, the magneto, support and driving connections being preferably formed as a unitary structure.

With these general objects in view, a preferred embodiment of my invention contemplates the provision of a magneto and suitable transmission gearing, all mounted upon a single support or bracket and capable of attachment as a unit in place of the original distributor head, and preferably by the use of the same attaching means.

A further feature of my invention is the provision of a supporting structure by which the magneto will be positioned with its armature vertically disposed and connected by very simple driving mechanism to the shaft from which the generator distributor head is commonly rotated, the driving mechanism being desirably located in part within a chamber formed between the magneto casing and the supporting structure.

I also provide an improved construction by which the magneto may be easily adjusted in correct timed relation to the engine.

My invention further relates to arrangements and combinations of parts which will be hereinafter described and more particularly pointed out in the appended claims.

One embodiment of the invention is shown in the drawings in which—

Fig. 1 is a vertical sectional end view of a portion of an engine casing having a magneto mounted thereon; and

Fig. 2 is a detail view showing the manner of attachment to a generator casing.

Referring to Fig. 1, I have shown a part of an engine casing 10 having a portion 11 extending laterally therefrom and providing a support for a drive shaft 12. This drive shaft 12 often drives the water pump and in a generator system is commonly connected through spiral gears with a vertical shaft upon which the contact arm of the generator distributor head is mounted.

In my improved construction, this vertical shaft and its bearing sleeve is removed and a casing or bracket 15 is inserted in place thereof, the bracket having a hub or extension 16 fitting in the casing 11 in place of the bearing of the discarded distributor head shaft. This bracket 15 should be of non-magnetic material, so that it may not deflect the lines of magnetic force.

A transmission shaft 17 is mounted in the hub 16 and is preferably provided with a spiral gear 18 at its lower end, meshing with a corresponding spiral gear 19 on the shaft 12. These gears may desirably be the original gears or of the same ratio.

A magneto indicated generally by the letter "M" is mounted on the support or bracket 15 and may be secured thereto by screws 20. The usual armature 21 is rotatably mounted in upper and lower bearings 22 and 23 in the magneto casing and is provided with a pinion 24 secured to the lower end of the armature shaft 25 and meshing with a gear 26 mounted on the upper end of the transmission shaft 17.

The gear 26 is commonly of twice the size of the pinion 24 for a four or eight cylinder engine, so that the armature may rotate twice as fast as the distributor arm of the original generator ignition. At its upper end the armature shaft 25 is preferably provided with a pinion 27 engaging

a gear 28 of twice its size. The gear 28 is thus driven at the same speed as the transmission shaft 17 and rotates the usual magneto distributor head, not shown. For a three, six or twelve cylinder engine, a three-to-one gear ratio is required.

The support 15 and the lower end of the magneto casing form a chamber for the gear 26 and pinion 24 in which they are 10 fully protected from dirt and injury. It is of course not essential that the magneto casing and the bracket 15 should always be formed as separate parts.

Anti-friction bearings 30 and 31 may be 15 provided for the shaft 17 in the support 15 and in the lower end of the magneto casing. A binding screw 32 is provided for securing the hub 16 in position, the end of 20 the screw seating in a groove 33 in the cylindrical outer surface of the hub.

With this construction, the magneto is 25 readily connected through very simple gearing to the usual drive shaft 12 and the simple bracket or support 15 permits the assembled magneto and transmission shaft 30 to be firmly mounted in place of the usual distributor shaft and head. The cylindrical hub 16 with its groove 33 and the binding screw 32 provide securing means which permits the bracket 15 to be moved angularly 35 with relation to the engine casing to accomplish the final adjustment of the necessary timing relation between the engine valves and the magneto distributor, the rough adjustment being accomplished by meshing 40 different teeth of the gears 18 and 19. It should be understood that the specific connections between the support 15 and the casing 11 will vary somewhat in different types 45 of engines and that the connections herein shown are illustrative of the connections for a single type only.

In Fig. 2, I have shown my invention applied to an engine in which the usual generator distributor head is mounted on the generator casing 35 and not on the engine casing. As in the previously described 50 form, the distributor head is removed and the hub 16 of the bracket 15 is inserted in place thereof, the driving connections from the generator shaft 36 preferably being as previously described.

Having thus described my invention, it 55 will be evident that changes and modifications can be made therein within the scope of my invention by those skilled in the art and I do not wish to be limited to the details herein disclosed otherwise than as set forth in the claims, but what I claim is:—

1. In a motor driven vehicle, in combination, a casing, a magneto, an armature shaft 60 rotatably mounted in said magneto, a support for said magneto, a transmission shaft mounted in said support, said support having an outwardly extending cylindrical bearing

hub for said transmission shaft and said casing having a cylindrical recess to receive said hub, means to secure said hub in said recess, a drive shaft in said casing, positive driving connections between said drive shaft 70 and said transmission shaft, and positive driving connections between said transmission shaft and said armature shaft.

2. In a motor driven vehicle, in combination, a casing, a magneto, an armature shaft 75 substantially vertically disposed therein, a support for said magneto, a transmission shaft mounted in said support parallel to said armature shaft, a positive driving connection between the upper end of said transmission shaft and the lower end of said armature shaft, means to secure said support on said casing, a drive shaft horizontally rotatable in said casing, and a positive driving connection between said drive shaft 80 and the lower end of said transmission shaft.

3. In a motor driven vehicle, a supporting casing, a magneto having an armature shaft and a magneto casing, a support for 90 said magneto secured to one end of said magneto casing and enclosing a chamber formed therewith, a transmission shaft mounted in said support, transmission gearing connecting said armature and transmission shafts and positioned in said chamber, 95 said support having an extension and said supporting casing having a corresponding opening, and means to secure said extension in said opening.

4. In a motor driven vehicle, a casing, a 100 drive shaft horizontally disposed therein, a magneto having an armature shaft, a support for said magneto, a transmission shaft mounted in said support parallel to said armature shaft, means to attach said support to said casing with said transmission and armature shafts in vertical position, positive gearing between the upper end of said transmission shaft and the lower end of said armature shaft, and a spiral gear connection 105 between said drive shaft and the lower end of said transmission shaft.

5. In a motor driven vehicle, a casing, a 110 drive shaft horizontally disposed therein, a magneto having an armature shaft, a support for said magneto, a transmission shaft mounted in said support parallel to said armature shaft, positive gearing between 115 said transmission shaft and said armature shaft, means to attach said support to said casing with said transmission and armature shafts in vertical position, and a spiral gear connection between said drive shaft and said transmission shaft, said attaching means permitting angular adjustment of said support to vary the timing relation of said magneto and engine.

6. In a motor driven vehicle, a casing, a 120 drive shaft in said casing, a magneto having an armature shaft, a supporting bracket for 125

said magneto, a transmission shaft mounted in said bracket, reduction gearing between said armature and said transmission shaft, means to directly secure said bracket to said 5 casing, and a gear connection between said drive shaft and said transmission shaft, said securing means permitting angular adjust-

ment of said bracket on said casing to vary the timing relation of said magneto and engine.

In testimony whereof I have hereunto affixed my signature.

JOSEPH C. TOWLER.
